CHANGE VALVE AND SEAT FOR MECHANICAL REFRIGERATION

Charles M. Goodland, Rock Island, Ill.

Application July 29, 1932, Serial No. 625,963

1 Claim. (Cl. 277—24)

The invention relates to a valve and seat and more especially to a changeable valve and seat for use in mechanical refrigerating systems.

The primary object of the invention is the provision of a valve and seat of this character wherein the same in their mounting will permit changing without requiring pumping the refrigerant agent from the refrigeration system and without the necessity for disconnecting any 10 pipe line or lines in the refrigeration equipment so that the use of a gas mask is dispensed with and also the loss of any material amount of gas avoided.

Another object of the invention is the provision of a valve and seat, wherein protection is had thereto against damage during shipment of the valve, particularly when installed in a refrigeration system of the iceless or mechanical kind and also permits repairs, replacement 20 or installation with dispatch and without removal of the refrigerant from the system or the boiler or boilers thereof and also eliminates all possibility of air or moisture entering the boiler or boilers.

A further object of the invention is the provision of a valve and seat of this character which are simple in construction, readily and easily changeable, thoroughly reliable and efficient in the operation thereof, easily repairable, and inexpensive to manufacture and install.

With these and other objects in view, the invention consists in the features of construction, combination and arrangement of parts as will be hereinafter more fully described in detail, illustrated in the accompanying drawing, which discloses the preferred embodiment of the invention, and pointed out in the claim hereunto appended.

In the accompanying drawing:

Figure 1 is an elevation of a header as mountable in a boiler or boilers of a refrigerating system showing the valve constructed in accordance with the invention.

Figure 2 is a side elevation thereof with the valve in association with a float.

Figure 3 is an enlarged vertical longitudinal sectional view through the valve and its seat.

Figure 4 is a sectional view on the line 4—4 of Figure 3 looking in the direction of the arrows.

Figure 5 is a sectional view on the line 5—5 of Figure 3 looking in the direction of the arrows.

Similar reference characters indicate corresponding parts throughout the several views in the drawing.

Referring to the drawing in detail, A design-

nates generally a header for a boiler of a refrigerating system of the iceless or mechanical type and B the float operative within the boiler (not shown). Carried by the header is the change valve and seat constituting the present invention and hereinafter fully described.

The valve comprises a body 10 which is fitted in the header A and is formed with external threads 11 for a clamping nut 12 in which is arranged a rotary valve 13, the same being held matched with the body 10 through the medium of the nut 12. Within the rotary valve 13 is a removable valve seat 14, the same being of substantially conical plug-like form and fits a like socket 15 formed in said rotary valve 13.

Formed in the valve body 10 is a guide passage 16 for a valve stem 17 pivoted to the arm 18 of the float B. This stem operates upon a needle valve 19 fitted within the valve seat 14 for controlling the port 20 as should be obvious from Figure 3 of the drawing.

The arm 18 of the float B is pivotally supported by a bracket 21 fitted with a valve body 10 and this bracket as well as the float B is of conventional construction.

Mounted on the outer face of the rotary valve 13 is the valve seat clamp 22 removably secured by a seat clamp stud 23 upon the rotary valve 13, the clamp being disposed against the valve seat to retain the same within the socket 15, the valve seat 14 being formed with a wrench engaging lug 24 and likewise the stud 23 is provided with a wrench engaging lug 25 so that the latter can be loosened or disengaged from the rotary valve 13 to release the clamp 22 in the use of a wrench, while the lug 24 will permit such wrench to be used for the loosening of the valve seat 14 or its removal from the rotary valve 13.

The rotary valve 13 has a ground joint with the valve body 10 and when it is desired to remove the seat 14 and the needle valve 15 without the escape of refrigerant through the lead 26 the nut 12 is loosened sufficiently to permit the rotary valve 13 to be turned a quarter turn, whereupon the lead 26 and the passage 16 will be closed. Thereafter the clamp 22 can be released by the stud 23 and the valve seat 14 removed as well as the needle valve 19. These parts may be readily changed in this manner or the same may be cleaned or reground for the proper functioning thereof. The seat 14 when cleaned, repaired or a new one may be placed in the socket 15 in the rotary valve 13 and the clamp 22 secured thereto in relation to said seat to make the same secure, whereupon the valve 13

is readjusted for the opening of the lead 26 in the passage 16 and thereafter the nut 12 is tightened to make secure against movement said rotary valve.

5 During shipment of the valve and its seat in a refrigerator of the iceless or mechanical type the seat 14 can be adjusted by rotating the valve 13 to shift the needle valve 19 out of contact with the valve stem 16 and thereby protecting the said 10 needle valve 19 and its seat from damage during shipment.

It should be obvious that the needle valve and its seat may be changed, renewed or replaced without pumping the refrigerant agent in the 15 refrigerating system out of the boiler or boilers and without necessitating the opening of the boiler or closing any other valve or valves in the equipment of the refrigerating system or disconnecting any pipe line or lines of such equipment 20 and eliminating the use of a gas mask and the possibility of air or moisture entering the boiler, the change, renewal or replacement being effected with dispatch and with the loss of minimum or no gas.

25

What is claimed is:

A valve of the kind described comprising inner and outer sections adapted for abutting relation to each other, the inner section being externally threaded for the mounting of the same with respect to a fluid source, the outer section forming a rotary valve and being reduced at its outer end, a collar receiving the outer and inner sections and threaded with the latter and having an outer open front for receiving the reduced outer end of the outer section, a plug-like valve seat 80 removably fitted in the outer section and having a turning stud at its lower end projected beyond the reduced outer end of the outer section, a needle valve in said seat for controlling a port through said seat and for coaction with a float arm, the said outer and inner sections having 85 passages controlled by the outer section, and means on the outer section and engaged with the removable seat to hold it fitted in the outer section and also to expose the turning stud of said seat.

CHARLES M. GOODLAND.
